[57] **CLAIM**

The ornamental design for a rollout message pen, as shown and described.

DESCRIPTION

FIG. 1 is a front perspective view of a rollout message pen showing my new design;

FIG. 2 is a rear perspective thereof;

FIG. 3 is an end elevational view thereof;

FIG. 4 is an end elevational view of the end opposite that shown in FIG. 3;

FIG. 5 is a perspective view of the design shown in FIGS. 1 through 4 with the sheet material in a retracted position;

FIG. 6 is an end elevational view thereof; and

FIG. 7 is an end elevational view of the end opposite that shown in FIG. 6.

Fig. 1.

Fig. 2.

Fig. 3.

Fig. 4.

Fig. 7.
